CONTIGUOUS ROTATION COUNTER

Leonard R. Harper, West Hempstead, N. Y., assignor to International Business Machines Corporation, New York, N. Y., a corporation of New York

Application June 26, 1948, Serial No. 35,391

3 Claims. (Cl. 177—380)

1

This invention relates to counting mechanism, and in particular, to devices for counting the number of rotations of a rotating shaft. More specifically, this invention is concerned with counting apparatus wherein the carry over from one numerical order to the next higher order is provided continuously rather than intermittently, as in most conventional counters where a lower order upon reaching its highest value produces a carry operation to bring about a single count in the next higher order.

Briefly, the present invention consists of a series of commutator shafts each of which carries one or more rotating electrical contacts co-operating with a closed series of fixed contacts for determining electrically the position of the shaft with respect to the fixed contacts. All of the shafts are geared together so that one revolution of a lower order shaft will produce an angular displacement in the next higher order proportional to the system of counting employed. For example, where the decimal system is used, as shown in the embodiment of the present invention, the commutator shafts are geared together to obtain a ten to one ratio; i. e., one revolution of the "units" shaft produces one tenth revolution of the "tens" shaft, one revolution of the "tens" shaft produces one tenth revolution of the "hundreds" shaft, et cetera. It is apparent, therefore, that in a device of this nature a one tenth revolution of the "tens" shaft will produce a one thousandth revolution of the "thousands" shaft or a one millionth revolution of the "millions" commutator shaft.

It is not feasible to utilize a commutator having a thousand segments or a million segments, nor is it practicable to advance a moving contact or a brush from one segment to the next of a commutator so constructed. In the present invention these difficulties are overcome using conventional commutators and an arrangement of cams and brushes carried by each commutator shaft. Normally each commutator shaft, except that of the units order, carries two brushes, one leading the other, arranged to have the leading brush make electrical contact with a commutator segment corresponding to a higher digital value in the order of that commutator and the lagging brush with a segment corresponding to a lower digital value. Each commutator shaft also carries a plurality of cams arranged to operate contacts at certain times as the shaft rotates to establish circuits to the leading and lagging brushes of the commutator shaft of the next higher order. The true value represented by the

2

rotation of the higher order shaft is determined thereby with reference to the commutator shaft of the next lower order in a manner to be described in detail hereinafter.

5 The principal object of this invention is, therefore, to provide means for electrical "read out" in a multiple commutator counter wherein the various orders of counting are represented by fractional rotations in each of a series of commutator shafts geared successively to one another in ratios corresponding to their numerical orders.

10 Another object of this invention is to provide means for determining the position of a rotating shaft of a series of intergeared shafts by reference to the next lower order of shaft in the series.

15 Other objects of the invention will be pointed out in the following description and claims and 20 illustrated in the accompanying drawings, which disclose, by way of example, the principle of the invention and the best mode, which has been contemplated, of applying that principle.

In the drawings:

25 Fig. 1 is a diagrammatic view, partially in section, showing the mechanical arrangement of the components of the invention.

Fig. 2 is a partial diagrammatic view of one of the commutators of the counter illustrating the 30 rotating and fixed electrical contacts forming a part of Fig. 1.

Fig. 3 is a timing chart showing the relation of the rotating and fixed contacts in a commutator under certain conditions of operation.

35 Fig. 4 illustrates diagrammatically the relationship between certain cam contacts forming a part of the electrical circuits of the invention.

Fig. 5 is a timing chart showing the relations 40 between the various cam contacts and commutator brushes involved in the electrical circuits for three numerical orders of the counter.

Fig. 6 is a wiring diagram of the invention illustrating the electrical circuits for four numerical orders of the counter.

45 Referring now to Fig. 1 a series of shafts US, TS, HS, and THS are geared together by the gears G—1, G—2, G—3, G—4, G—5, G—6, G—7, G—8, G—9, G—10, G—11, and G—12 so that the shafts rotate respectively in ratios of 1:10; i. e., 50 shaft HS rotates ten revolutions for each revolution of shaft THS, shaft TS rotates ten revolutions for each rotation of shaft HS, and shaft US rotates ten revolutions for each revolution of shaft TS. Each of the aforementioned shafts carries fixed to one end an insulated rotor; i. e.,

shaft US has a rotor UR, shaft TS has a rotor TR, shaft HS a rotor HR, and shaft THS a rotor THR. Each of the rotors is provided to carry a pair of contact brushes LB and BL insulated from each other and terminating, as shown in Fig. 1, respectively in the telescoping contacts CLB and CBL. Each pair of contact brushes LB and BL coats with a closed series of contact segments SG contained in a commutator block surrounding each rotor: commutator block UCM surrounding rotor UR, block TCM surrounding rotor TR, block HCM surrounding rotor HR, and block THCM surrounding rotor THR. Each of these blocks also carries a pair of contact plates, CCLB which is contacted by the telescoping contact CLB, and CCBL which is contacted by the telescoping contact CBL. Each segment SG is connected to a terminal CMC in the top of a block, there being ten segments SG and ten terminals CMC equally spaced about each block.

Fig. 3 illustrates in detail the relation of the brushes LB and BL, the contacts CLB and CBL, and the segments SG. Each of the commutators is identical; however, the commutator formed by the rotor UR and the block UCM, together with their brushes, contacts, and segments is only partially used since normally no electrical circuits are completed through the brush BL and the contact CBL. In all of the other commutators, however, both brush LB and brush BL are used to complete electrical circuits with the segments SG. The size and spacing of the segments SG and the spacing of the brushes LB and BL with respect to the segments SG and to each other is an essential feature in the subject invention. In Fig. 2 it is to be noted that both brushes LB and BL may contact the same segment SG at the same time and that the brush LB may be on one segment SG while the brush BL is on a following segment SG relative to the direction of rotation of a shaft S which carries a rotor having the brushes LB and BL, as shown in Fig. 2.

The novelty attainable with the arrangement of commutators in the subject invention relative to the brush and segment relationship is best illustrated diagrammatically by Fig. 3. Let it be assumed that the commutators represented by the block UCM-rotor UR and the block TCM-rotor TR represent, respectively, the "units" order and the "tens" order in a decimal counter so that for each complete revolution of the rotor TR, the rotor UR will make ten revolutions following an arrangement of gearing as in Fig. 1, and a commutator segment-brush arrangement as in Fig. 2. Let it be assumed, further, that the segments shown as "2," "3," and "4" (see Fig. 3) represent segments SG in the "tens" commutator and that the arrows LB and BL respectively represent the leading and lagging brushes of the rotor TR in the "tens" commutator. It is obvious that when the rotor UR makes one complete revolution, the brushes LB and BL in the "tens" commutator will advance from one position respective to the segment "2" to a similar position respective to the segment "3," there being ten segments equally distributed in the path of the brushes LB and BL in the "tens" commutator. Referring now to Fig. 3, when the single active brush of the "units" commutator is contacting the "0" segment the brush LB is on the "3" segment of the "tens" commutator and the brush BL is on the "2" segment of the "tens" commutator. When the brush in the "units" order is at the "1" segment, the brush

LB is on the "3" segment of the "tens" order and the brush BL is between the "2" and the "3" segments of the "tens" order. The brushes LB and BL thereafter advance, as shown in Fig. 3, in accordance with the value in the "units" order until they occupy a final position upon the segments "3" and "4" of the "tens" order similar to their initial position on the "2" and "3" segments of the "tens" order thereby indicating a complete revolution of the "units" order brush through each of its ten values "0" to "9," inclusive.

Returning to Fig. 1 it will be observed that each of the shafts US, TS, and HS carry a plurality of cams. For example, the "units" shaft US carries a high selection cam USC-1 coacting with a pair of contacts H and a low selection cam USC-2 coacting with a pair of contacts L. The "tens" shaft TS carries a high transfer cam TTC-1 coacting with a pair of contacts H, a low transfer cam TTC-2 coacting with a pair of contacts L, a high selection cam TSC-1 coacting with a pair of contacts H, and a low selection cam TSC-2 coacting with a pair of contacts L. The "hundreds" shaft HS carries cams identical with those carried by the "tens" shaft TS. The "thousands" shaft THS, being the highest order shown in the embodiment herein, does not carry any cams; however, for higher orders of commutators above the "units" order, in a counter of the type herein disclosed, each order except the last or highest order is provided with four cams similar to those carried by the shafts TS and HS.

Fig. 4 shows the relative positions when cam contacts are closed based upon a complete revolution of the same order commutator. The selection cams of an order are timed to close their contacts in accordance with the values represented in that order commutator. For example, when the "units" order represents values between "0" and "4," the low selection cam contacts are closed while when the values lie between "5" and "9" in the "units" order the high selection cam contacts are closed in the "units" order. These cam contacts are timed to be closed to provide an overlap at the "4" and "5" values. Normally the higher selection cam contacts of one order are connected electrically to the lagging brush of the next higher order and the low selection cam contacts are connected to the leading brush of the next higher order. For example with reference to Fig. 6, the contacts H of the high selection cam USC-1 of the "units" order are connected to the lagging brush BL of the "tens" order, and the contacts L of the low selection cam USC-2 of the "units" order are connected to the leading brush LB of the "tens" order. Those orders which have transfer cams, i. e., all orders except the lowest and the highest, have the high transfer cam contacts connected to the lagging brush of the same order and the low transfer cam contacts connected to the leading brush of the same order. For example, the contacts H of the high transfer cam TTC-1 are connected to the lagging brush BL of the "tens" order, and the contacts L of the low transfer cam TTC-2 are connected to the leading brush LB of the "tens" order.

Fig. 6 illustrates the electrical circuits necessary for a counter capable of counting to a total of 9999, there being four commutators as previously described in Fig. 1, each having ten counting positions "0" through "9" represented by ten segments SG, each of these being provided with an electrical terminal CMC. Relay coils UM are connected from each terminal CMC in the "units" order commutator to a common line B, similar

coils TM are connected from each terminal CMC in the "tens" order to the line B, coils HM being similarly arranged in the "hundreds" orders, and coils THM in the "thousands" order. In the operation of the counter, described later herein, circuits are completed from the line B, via the battery V, the key switch K, line A, and the various cam contacts to the brushes LB and BL which make contact with segments SG in each of the commutators to energize coils UM, TM, HM, and THM in accordance with the total value in the counter. The aforesaid coils may operate relay contacts to control electrical indicators or electromagnetic punching devices in order to obtain a record of the value in the counter according to well known methods commonly employed in punched card machines.

The operation of the subject invention is best understood by reference to Figs. 1, 5, and 6. Let it be assumed that the shaft US is turned by a device, the number of revolutions of which is to be measured, the device being geared to the shaft US so that one revolution of the shaft US equals ten revolutions of the aforesaid device; i. e., each position of the brush LB of the "units" order upon a segment SG representing a revolution of the device. Let it be further assumed that all the commutators are set to zero; i. e., with their leading and lagging brushes LB and BL positioned respectively on the "0" and "9" segment SG positions similar to the first position shown in Fig. 3, the units order having its single active brush LB on "0." Suppose that before any shaft revolves the switch K is closed. Circuits will then be completed as follows: (1) Battery V, line B, "0" position coil UM, "0" position contact CMC of "units" order, brush LB of "units" order, line W-1, line A, switch K, to battery V. (2) Battery V, line B, "0" position coil TM, "0" position contact CMC of "tens" order, brush LB of "tens" order, line W-12, contact L (now closed) of low selection cam USC-2, line W-1, line A, switch K, to battery V. (3) Battery V, line B, "0" position coil HM, "0" position contact CMC of "hundreds" order, brush LB of "hundreds" order, line W-13, contact L (now closed) of low selection cam TSC-2, line W-10, line A, switch K, to battery V. (4) Battery V, line B, "0" position coil THM, "0" position contact CMC of "thousands" order, brush LB of "thousands" order, line W-6, contact L (now closed) of low selection cam HSC-2, line W-11, line A, switch K, to battery V. Consequently, the "0" position relay coils UM, TM, HM, and THM will be energized and the counter will read a value of 0000. Presume now that the device turning the shaft US is permitted to rotate until the instant when the brush LB of the "tens" order rests on the "5" segment SG and the brush BL rests on the "4" segment SG and the "units" order brush LB rests on the "9" segment SG whereupon the switch K is closed again. Circuits will now be established: (1) Battery V, line B, "9" position coil UM, "9" position contact CMC of "units" order, brush LB of "units" order, line W-1, line A, switch K, to battery V. (2) Battery V, line B, "4" position coil TM, "4" position contact CMC of the "tens" order, brush BL of "tens" order, line W-8, contact H (now closed) of high selection cam USC-1, line W-1, line A, switch K, to battery V. (Circuits for the hundreds and thousands orders are established as previously.) The value thereby read from the counter is 0049. Let it now be presumed that the shaft US is rotated one tenth of a revolution so that the brush LB falls

on the "0" segment SG of the "units" order while the brushes LB and BL of the "tens" order advance one hundredth of a revolution remaining on the segments SG of the "tens" order commutator at the "5" and "4" positions, respectively. If at this time the switch K is again closed a circuit will be established to energize the "0" position coil UM, as previously described; however, the circuit established in the "tens" order will be: Battery V, line B, "5" position coil TM, "5" position contact CMC, brush LB of tens order, line W-12, contact L (now closed) of low selection cam USC-2, line W-1, line A, switch K, to battery V. Consequently, the value read from the counter is then 0050. In other words, the distinction in the last two examples of counter values read from the counter is dependent upon the contacts controlled by the cams USC-1 and USC-2, i. e., the high selection and low selection cams.

The action of the "hundreds" order circuits for reading values from the counter are similar to those of the "tens" order. While the high and low selection cams for the "tens" order are carried by the "units" order shaft US, the high and low selection cams for the "hundreds" order are carried by the "tens" order shaft TS. Consequently, for an advance of one position in the "units" order while the "tens" order selection cams advance one position, the "hundreds" order selection cams advance only one tenth of a position. It is to be noted that the high selection cam USC-1 and low selection cam USC-2 are carried by the "units" order shaft US (see Fig. 1), these cams governing the selection of the brushes BL and LB of the "tens" order. Since there is 36 degrees of rotation of the "units" order shaft US from the "9" to the "0" position the timing of these cams is not critical. On the other hand the high selection cam TSC-1 and the low selection cam TSC-2 which govern the selection of the brushes BL and LB of the "hundreds" order are carried by the "tens" order shaft TS wherein there is only 3.6 degrees of rotation for a rotation from the "9" to the "0" positions of the "units" order shaft US. Similarly the high selection cam HSC-1 and the low selection cam HSC-2 are carried by the "hundreds" order shaft HS wherein there is only .36 degree of rotation for a rotation from the "9" to the "0" positions of the units order shaft US. It is obvious therefore that in the higher orders the timing of the high and low selection cams becomes exceedingly critical and tends to become uncertain.

Uncertain timing resulting in errors in the higher orders of the device, particularly when the shafts US and TS rotate at high speeds, is eliminated by providing pairs of cams TTC-1, TTC-2 and HTC-1, HTC-2, previously referred to as high transfer and low transfer cams on the intermediate ("tens" and "hundreds") orders shafts TS and HS, the timing of these cams being shown specifically in Fig. 5 and, in comparison with the selection cams, in Fig. 4.

When the "tens" order shaft TS advances from its "9" position to its "0" position, i. e., for counter values from 90 to 100, 190 to 200, 290 to 300, etc., the transfer cams become effective in establishing electrical circuits. Let it be assumed that the value read from the counter is 495 so that when switch K is closed circuits are established as follows: (1) Battery V, line B, "4" position coil HM, "4" position contact CMC "hundreds" order, brush BL, "hundreds" order,

line W-9, H contacts of high selection cam TSC-1, line W-10, line A, switch K, to battery V. (2) Battery V, line B, "9" position coil TM, "9" position contact CMC "tens" order, brush BL of "tens" order, line W-8, high selection cam USC-1, line W-1, line A, switch K, to battery V. (3) Battery V, line B, "5" position coil UM, "5" position contact CMC "units" order, brush LB "units" order, line W-1, line A, switch K, to battery V. The value read is therefore 495. With reference to Fig. 5, it will be observed that at a time slightly later the high transfer cam TTC-1 of the "tens" order closes its contacts H thereby providing a parallel circuit for the "hundreds" order as follows: Battery V, line B, "4" position coil HM, "4" position contact CMC "hundreds" order, brush BL of "hundreds" order, line W-9, H contacts of high transfer cam TTC-1, line W-3, line W-8, H contacts of high selection cam USC-1, line W-1, line A, switch K, to battery V. Slightly later as the shafts US, TS, and HS continue rotating, the high selection cam TSC-1 opens its contacts H, leaving the "hundreds" order circuit completely under control of the contacts H of the high selection cam USC-1.

Further movement of the shafts US, TS, and HS (as values of 496 and 497 are read out via circuits previously described) causes the contacts L of the low transfer cam TTC-2 to close so that a circuit from the brush LB of the "hundreds" order is completed via line W-13, L contacts of low transfer cam TTC-2, line W-2, to L contacts of low selection cam USC-2. The cam USC-2, however, does not close its contacts L until the "units" order brush LB falls on the "0" position segment SG of the "units" order commutator.

The conditions for a value of 499 in the counter are similar to those just described except that the units order advances its brush LB to the "9" position segment of the "units" order commutator. However, when the "units" order advances its brush LB to the "0" position segment SG of the "units" order commutator the contacts H of the high selection cam USC-1 open and the contacts L of the low selection cam USC-2 close so that when switch K is closed, circuits are established: (1) Battery V, line B, "5" position coil HM, "5" position contact CMC of "hundreds" order, brush LB of "hundreds" order, line W-13, L contacts of low transfer contact TTC-2, line W-2, L contacts of low selection cam USC-2, line W-1, line A, switch K, to battery V. (2) Battery V, line B, "0" position coil TM, "0" position contact CMC of "tens" order, brush LB of tens order, line W-12, L contacts of low selection cam USC-2, line W-1, line A, switch K, to battery V. (3) Battery V, line B, "0" position coil UM, "0" position contact CMC "units" order, brush LB of "units" order, line W-1, line A, switch K, to battery V. The value read out thereby is 500.

The establishment of read out circuits for the "thousands" order is similar to that of the "hundreds" order. For example, for a counter value of 4999 the "thousands" order circuit is from battery V, line B, "4" position coil THM, "4" position contact CMC, brush BL of "thousands" order, line W-7, contacts H of high transfer cam HTC-1, line W-5, line W-9, contacts H of high transfer cam TTC-1, line W-3, line W-8, contacts H of high selection cam USC-1, line W-1, line A, switch K, to battery V. For a counter value of 5000 the "thousands" order

circuit is from battery V, line B, "5" position coil THM, "5" position contact CMC, brush LB of "thousands" order, line W-6, contact L of low transfer cam HTC-2, line W-4, contact L of low transfer cam TTC-2, line W-2, contact L of low selection cam USC-2, line W-1, line A, switch K, to battery V.

Thus it is apparent that the selection of the leading brushes LB and the lagging brushes BL in any order is always referred back to the lower order or orders when the aforesaid brushes are upon adjacent segments as has been shown. In this manner accuracy of a high degree may be obtained with no more than four operating contacts per order of a counter.

It is to be noted that no error results from the overlap of the high and low selection cams at the "4" and "5" positions (see Fig. 4 and Fig. 5) if the brushes LB and BL of the next higher order are set equally on "0" and "9" positions respectively, when the next lower order is midway between the "9" and the "0" positions. This is due to the fact that when the next lower order advances five positions, the brushes LB and BL in next higher order will advance to make contact with the same segment at which time the high and low selection cam contacts of the next lower order are both closed (see line y-y', Fig. 4), it being immaterial by which circuit path the read out circuit is established.

While there have been shown and described and pointed out the fundamental novel features of the invention, as applied to a preferred embodiment, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In combination with three interacting commutators each having a predetermined number of equally spaced conductive segments arranged in a closed series and a pair of coordinately rotatable brushes coacting therewith and spaced apart to alternately make mutual contact with one said segment and independent contact with adjacent segments thereof, means for rotating the brushes of a first commutator comprising a rotatable shaft, a second shaft geared to the first shaft for rotating the brushes of a second commutator, a third shaft similarly geared to the second shaft for rotating the brushes of a third commutator, a pair of circuit breakers on the first shaft, two pairs of circuit breakers on the second shaft, circuit connections for establishing a circuit to one of the segments of the third said commutator through one said third commutator brush including one of the first pair of circuit breakers on the second said shaft and one of the circuit breakers on the first said shaft, and circuit connections for establishing a circuit to the same segment of the third said commutator through the same third commutator brush including one of the second pair of circuit breakers on the second said shaft.

2. The invention as set forth in claim 1 with a further provision that the rotation ratio of the first shaft to the second shaft and the ratio of the second shaft to the third shaft is equal to the number of conductive segments in each commutator.

3. In a device for counting the revolutions of

1 shaft comprising a plurality of commutators having rotating elements seriatim coupled to the said shaft, each of the said elements rotating with respect to the said shaft in predetermined decreasing ratios; a pair of brushes carried by each said element, the said brushes being electrically independent of each other and one brush leading the other by a predetermined amount; a predetermined number of contacts spaced equally upon each said commutator, the contacts being of a size and arrangement to be engaged successively by the said leading and lagging brushes either singly or in combination; and a pair of circuit breakers carried by the said element of each order, one of the said circuit breakers of each order being timed to close a circuit to the lagging brush of a higher order during contact of a lower order commutator

5 brush with the first half of its said contacts, and another of the said circuit breakers of each order being timed to close a circuit to the leading brush of a higher order commutator during contact of the lower order commutator brush with the second half of its said contacts.
